CLAIM

The ornamental design for a tool, as shown and described.

DESCRIPTION

FIG. 1 is a rear perspective view of our new design for a tool; FIG. 2 is a front perspective view of FIG. 1;

FIG. 3 is a left side view of FIG. 1;

FIG. 4 is a right side view of FIG. 1;

FIG. 5 is a front view of FIG. 1;

FIG. 6 is a rear view of FIG. 1;

FIG. 7 is a top view of FIG. 1;

FIG. 8 is a bottom view of FIG. 1;

FIG. 9 is a rear perspective view of our second new design for a tool;

FIG. 10 is a front perspective view of FIG. 9;

FIG. 11 is a left side view of FIG. 9;

FIG. 12 is a right side view of FIG. 9;

FIG. 13 is a front view of FIG. 9;

FIG. 14 is a rear view of FIG. 9;

FIG. 15 is a top view of FIG. 9;

FIG. 16 is a bottom view of FIG. 9;

FIG. 17 is a rear perspective view of our third new design for a tool;

FIG. 18 is a front perspective view of FIG. 17;

FIG. 19 is a left side view of FIG. 17;

FIG. 20 is a right side view of FIG. 17;

FIG. 21 is a front view of FIG. 17;

FIG. 22 is a rear view of FIG. 17;

FIG. 23 is a top view of FIG. 17; and,

FIG. 24 is a bottom view of FIG. 17.
